DESIGN FOR A WALL BRACKET

John C. Meeks, Woodland, Calif.

Application February 29, 1944, Serial No. 112,748

Term of patent 3½ years

(Cl. D33—3)

To all whom it may concern:

Be it known that I, John C. Meeks, a citizen of the United States and a resident of the city of Woodland, county of Yolo, State of California, have invented a new, original, and ornamental Design for a Wall Bracket, of which the following is a specification, reference being had to the accompanying drawing, forming a part hereof.

Figure 1 is a top plan view of a wall bracket, showing my new design; and

Figure 2 is a front elevational view thereof.

I claim:

The ornamental design for a wall bracket, as shown.

JOHN C. MEEKS.
